(57) **CLAIM**

The ornamental design for a dual wide-screen gaming machine, as shown and described.

DESCRIPTION

FIG. 1 is a perspective view of a gaming machine, showing my new design;

FIG. 2 is a front elevational view thereof;

FIG. 3 is a right side elevational view thereof; and,

FIG. 4 is a rear elevational view thereof.

The broken line showing is for illustrative purposes only, and forms no part of the claimed design.
